UNITED STATES PATENT OFFICE.

THOMAS J. MURPHY, OF SAN FRANCISCO, CALIFORNIA.

TRAIN-PIPE COUPLING FOR RAILWAY-COACHES.

No. 838,043.

Specification of Letters Patent.

Patented Dec. 11, 1906.

Application filed November 15, 1905. Serial No. 287,395.

To all whom it may concern:

Be it known that I, THOMAS J. MURPHY, a citizen of the United States, residing in the city and county of San Francisco and State of California, have invented new and useful Improvements in Train-Pipe Couplings for Railway-Coaches, of which the following is a specification.

This invention relates to an improved means or device for connecting the hose or pipe of air-brakes, the electric wires, and other parts that require to be connected and disconnected between railway-coaches in making up and breaking up a train; and the invention has for its object the production of a simple and effective union-coupling by which all the parts to be coupled and uncoupled between two coaches are united or separated at the same time and by the same movement or operation that couples or uncouples the coaches, thereby reducing both the risk heretofore attending the work of the brakeman and the time and labor of making up or separating a train of coaches.

To this end and object my invention consists in an improved construction of coupling-head having a plurality of channels or passages through it and provided with means for connecting or attaching the train-pipes, electric wires, and other parts and accessories of the brake mechanism and the lighting and heating apparatus that are located beneath the floor of the coach, the coupling-head being adapted to interlock with another head of the same construction on the other coach, with which it forms a complete coupling device between the two coaches when the same are connected together in making up a train, all as hereinafter described, and pointed out in the claims at the end of this specification.

In the accompanying drawings, herein referred to, Figure 1 represents a coupling device embodying my invention and suspended in position under the draw-heads on two coaches. In this figure the coupling device is represented in general outside view, and the floor of the coaches and the running-gear are shown in section. Fig. 2 is a side view of the coupling-head on one coach, showing the same in the position it occupies when the two coaches are uncoupled. Fig. 3 is a plan or top view of the coupling device, one of the coupling-heads and a portion of the adjoining end of the other coupling being shown in section. Fig. 4 is a longitudinal section, on an enlarged scale, through the two coupling-

heads. Fig. 5 is a detail, on an enlarged scale and in a section taken horizontally, showing the two outer and adjoining knuckles on the two coupling-heads in position for interlocking.

In the following description the principal parts are referred to as the coupling-head *a* and the coupling-head *a'*, constituting the coupling device between two cars or coaches. The adjoining interlocking ends of the two heads are formed or provided with knuckles *d d'*, separated by recesses *c c'*, the knuckles on one head being set in line with the recesses in the opposite head, so that the two heads are interlocked when they are brought up together from opposite directions.

In the present construction provision is made for connecting two train-pipes or other conductors *T T'* on one coach with corresponding conductors *T² T³* on the other coach, and a set of electrical conductors *E E'* (indicated in Fig. 3) and the coupling-heads have each a separate channel or passage *b* for each pipe extending through the head from end to end and also a separate channel *e* for the electric wires. Threaded sockets *f* in the back of the coupling-head furnish means for connecting the pipes to their respective panels in the head; but other means for securing the pipes to the head could be used—such, for example, as the well-known pipe or hose coupling in which one part screws into or interlocks with the other part. The well-known binding-post *k*, used in making electrical connection, is provided on the back of the coupling-head for connecting the electric wires. The passages *b*, extending through the head from the end where the pipe is coupled to the front end, where the interlocking knuckles are formed, as seen in Fig. 3, is turned at right angles, as, at *b²*, and carried through the side of the knuckle in one head, so as to coincide with the corresponding passage *b* in the opposite coupling-head, when the knuckles of the two heads are interlocked. In such position it will be seen that the two channels *b b'* form a continuous passage through both heads and the interlocking knuckles. A tight joint is secured between the opposing faces of the knuckles that set together when the two heads are interlocked by providing a recess *i* in the face of one knuckle and a corresponding recess in the face of the other knuckle, in which recesses are fitted two rings *g g'*, having inclined faces. An elastic or spring washer *h* within the re-

cess behind each ring presses the same outward, so that the inclined face of the ring will stand slightly above the inner face of the knuckle. A face-plate k' , surrounding the projecting portion of the ring, confines it in place within the recess. By virtue of this construction (seen in Figs. 4 and 5) a tight joint is secured between the opposing faces of the two knuckles around the channels or passages that pass through the knuckles at right angles when the two heads are brought together. The inclined faces of the parts g are fitted to meet and slide smoothly upon each other, so as to register and bring the passages b^2 in line. Similarly-formed inclined plates g^3 are provided in the knuckles, through which the electrical wires are coupled; but in that part of the head the plates g^3 are made of some conducting metal, so as to afford the necessary electrical connection between the wires in the two heads when the latter are interlocked. In connection with this coupling device I have provided a means for automatically bringing the two heads in position to meet and interlock at the moment that the draw-heads D of the two coaches come together in the operation of coupling, so that it is not necessary for the brakeman to go in between the cars to set or regulate the coupling-heads. This means consists of a short lever m , working on a pivot m' and having attached to the end above the pivot a push-rod p , the lower end of the lever being carried from the pivot m' downward, so as to bear against the back of the coupling-head. A coiled spring r , surrounding a draw-rod s , which is secured to the back of the coupling-head, acts to draw the head back and hold it in position within the line of the front face of the draw-head D . This is the normal position of the coupling-head when one coach is not coupled to another.

The push-rod p , extending forward over the top of the coupling-head, projects beyond the line of the draw-head D and stands in a plane with the corresponding push-rod of the opposite head, so that the ends of the two rods make contact and are pressed together as the draw-heads of the two cars being coupled come together. By this means the push-rods press the coupling-heads into each other and cause their knuckles to interlock at the same time that the cars are coupled. The coupling-heads are suspended from the draw-head or the understructure of the car by straps or links t , attached to the sides of the coupling-head w , or they may be supported on the car-body, that will hold them properly in line and at the same time allow the necessary backward-and-forward play of the coupling when the two heads are interlocked.

All the pipes and other conductors and parts that require to be coupled between coaches in making up a train can be brought together and provided with separate pas-

sages and channels in a single coupling-head in accordance with my invention, as above described, with many advantages over the methods heretofore employed of connecting such pipes and accessories by individual couplings.

Having thus described my invention, what I claim as new, and desire to secure by Letters Patent, is—

1. A train-pipe coupling comprising two coupling-heads having each a plurality of channels or passages extending through the head from end to end, means on one end of the head for permanently connecting the train-pipes, knuckles on the opposite end through which the said channels or passages are carried to the outside, the knuckles on one head being alternately arranged with reference to the knuckles on the other head to interlock therewith, the channels or passages in the opposing knuckles being adapted to register and means, independent of the coupling-head for causing the said heads to move into engagement with each other.

2. A train-pipe coupling comprising two coupling-heads each having a plurality of channels or passages extending therethrough from end to end, means at one end of each of the heads for permanently connecting the train-pipes, knuckles, on the opposite ends through which the said channels or passages are carried to the outside, the knuckles being arranged to interlock with each other, springs for holding the coupling-heads in retracted position when not coupled together, and levers for moving the coupling-heads together when two cars are coupled, substantially as set forth.

3. In a train-pipe coupling, the combination of the two coupling-heads having each a plurality of channels or passages extending through the head from end to end, means on one end of the head for permanently connecting the train-pipes, knuckles on the opposite end through which the said channels or passages are carried to the outside, the knuckles on one head being alternately arranged with reference to the knuckles on the other head to interlock therewith, and the channels or passages in the opposing knuckles being adapted to register, and packing-plates in the opposing faces of the knuckles through which the channels or passages in the two heads are brought in communication, the said plates having oppositely-inclined faces.

4. In a train-pipe coupling, the combination of two coupling-heads having alternately-arranged knuckles on the adjacent ends of the two heads, adapted to interlock when the two heads are brought together, channels or passages extending through the heads and through the opposing faces of the knuckles, yielding plates in the opposing faces of the knuckles having inclined faces, the face of the yielding plate on one knuckle

being correspondingly inclined to the plate on the knuckle of the opposite head.

5. In a train-pipe coupling, the combination of two coupling-heads containing a plurality of channels or passages extending through the head, means for permanently connecting pipes and other parts to the channels or passages at one end, interlocking-knuckles on the opposing ends of the heads through which the channels or passages continue to the outside, the knuckles on one coupling-head being alternately arranged with reference to the knuckles on the other coupling-head, packing-plates between the opposing faces of the knuckles and means for bringing the two coupling-heads together at

the time of coupling the ends of two coaches on which the coupling-heads are fixed, comprising a draw-rod attached to each coupling-head adapted to move in one direction and a 20 rocking lever and a push-rod attached to the lever and extending in a line with the coupling-head and beyond the front end thereof for moving the coupling-head in the opposite direction.

In testimony whereof I have hereunto set my name to this specification in the presence of two subscribing witnesses.

THOMAS J. MURPHY.
